INVENTOR

Joseph Richard O'Reilly
BY
Thomas Drew Stetson
ATTORNEY.

UNITED STATES PATENT OFFICE.

JOSEPH RICHARD O'REILLY, OF Booterstown, Ireland.

PACKING-ENVELOP FOR BOTTLES.

SPECIFICATION forming part of Letters Patent No. 616,583, dated December 27, 1898.

Application filed March 8, 1898. Serial No. 673,042. (No model.)

To all whom it may concern:

Be it known that I, JOSEPH RICHARD O'REILLY, a subject of the Queen of Great Britain and Ireland, and a resident of Booterstown, in the county of Dublin, Ireland, have invented a new or Improved Packing-Envelop for Bottles, (for which I have obtained provisional protection in the United Kingdom of Great Britain and Ireland, dated 10 November 22, 1897, and numbered 27,320;) and I do hereby declare that the following is a full, clear, and exact description of the invention, which will enable others skilled in the art to which it appertains to make and use the 15 same.

The invention has reference to a new or improved packing-envelop for bottles of simple, light, and efficient construction.

In carrying out my invention I propose to 20 utilize, preferably, that type of paper commercially known as "corrugated paper," although suitable cardboard paper may be used if found equally effectual. This paper I treat in the following manner, reference being made 25 to the accompanying drawings, in which—

Figure 1 is a face view of the blank; Fig. 2, a side view of the envelop when partially completed; Fig. 3, a similar view after completion, the dotted lines showing the bottle 30 in closed. Fig. 4 shows the completed envelops empty and flattened. Fig. 5 is a plan view of a dozen properly packed together, and Fig. 6 is a corresponding end view. Fig. 7 is on a larger scale. It is a top view of the envelop 35 fully completed.

Similar letters of reference indicate corresponding parts in all the figures where they appear.

I take a piece of sufficient dimensions to 40 completely embrace the bottle for which the envelop A is intended, and I proceed to prepare the upper edge by cutting two tapering flaps A' A' and two rectangular flaps A² A², as shown in Fig. 1, or, if found more convenient, four tapering flaps may be provided, as indicated by the dotted lines. The material thus prepared is then rolled into a cylindrical form, as in Fig. 2, and its meeting edges B are secured by pasting, sewing, or by paper-

clips or other suitable means B'. The points 50 of the two tapering flaps A' A' are then brought together and fastened by a paper-clip or other suitable contrivance C. We have thus a cylindrical case or envelop with a straight edge at the bottom and the upper portion consisting of two tapering flaps connected at their points and two rectangular flaps standing free in line with the body of the case or envelop. The tapering flaps A' A' thus form a wedge-shaped end, which serves most usefully in 60 packing.

In practice it may not be found necessary to fasten the points of the tapering flaps A' together; but I consider it best to do so, since it insures the holding of these flaps in a more 65 accurate position to receive the overlapping of the rectangular flaps A² A², which are afterward pressed inward and folded on the other parts, as indicated in Fig. 7. The construction insures the envelop readily adapting 70 itself to the wedge-shaped principle in the operation of packing, as illustrated in Fig. 5. The envelop as thus prepared is slipped over the bottle M, to the formation of which it readily accommodates itself, as illustrated in 75 Fig. 3.

Fig. 4 shows the envelop pressed into a flat condition for storage or portable purposes.

Fig. 5 illustrates the manner in which the improved envelop accommodates itself in 80 packing. The figure represents a one-dozen case, which, owing to the compactness of each envelop, admits of the case being of much smaller dimensions than the ordinary one-dozen case at present in use.

Having now particularly described and ascertained the nature of my said invention and in what manner the same is to be performed, I declare that what I claim is—

1. In the packing of bottles, the envelop 90 described, cut from paper or analogous material, comprising flaps A', A', A², A², arranged as shown, on the upper edge, two of which form wedge-shaped terminations secured together and the other two being free 95 and forming guards at the sides of the secured flaps, thereby facilitating the safe packing of bottles in small space, and insuring

their safety in transit, substantially as and for the purpose herein specified.

2. The combination with a bottle M, of an envelop of corrugated paper A cut as shown 5 so as to form flaps on the upper edge, one pair of flaps A', A'', tapered and the other pair A², A², rectangular, the former being secured by fastenings C, and the latter left free to

constitute guards at the sides of the secured flaps, all arranged to serve substantially as 10 and for the purposes herein specified.

Dated this 23d day of February, 1898.

JOSEPH RICHARD O'REILLY.
